UNITED STATES PATENT OFFICE.

CHARLES Q. C. LEIGH, OF CHICAGO, ILLINOIS.

BOX.

1,209,178.

Specification of Letters Patent. Patented Dec. 19, 1916.

Application filed January 7, 1916. Serial No. 70,728.

To all whom it may concern:

Be it known that I, CHARLES Q. C. LEIGH, a citizen of the United States, and a resident of the city of Chicago, county of Cook, 5 and State of Illinois, have invented certain new and useful Improvements in Boxes, of which the following is a specification.

My invention relates to storing and shipping receptacles and more particularly to 10 a knock-down or foldable box or crate for fruit, vegetables, and the like.

The primary object of my invention is the provision of a foldable box or crate that may be knocked down into a flat condition for 15 shipment from the manufacturer to the consumer in order that they may be packed in large quantities in a comparatively small area, in railway cars, wagons or other vehicles, for transportation.

Another object of my invention is the provision of a foldable box or crate that may be quickly and easily assembled in shape for 20 the storage of commodities without the use of special tools and forms or the employment of a skilled mechanic.

Still another object is the provision of a receptacle of the type described that will permit the use of one of the side-walls as a 25 cover and the same adapted to be hinged or flexibly secured to the upper edge of the adjacent side-wall.

A further object of my invention is the provision of a box or crate that is durable when in use, simple in construction, easy to 30 operate, and comparatively inexpensive to manufacture.

Further objects of my invention will be obvious to others skilled in the art to which it pertains, after an understanding is had of 35 the accompanying specification and the drawings forming a part thereof.

In the drawings, similar reference characters are employed to designate the same parts throughout the divers figures.

Figure 1 is a perspective view of a box or 40 crate made in accordance with my invention, one of the side-walls whereof is raised slightly to illustrate the manner of using said wall as a cover. Fig. 2 is a transverse 45 vertical section taken on line 2—2, Fig. 1. Fig. 3 is a fragmentary detail of one of the upper corners of the box or crate drawn to an enlarged scale and illustrating the manner of securing the cover. Fig. 4 is a perspective view of my improved box or crate 50 in knocked-down or unfolded condition,

Fig. 5 is a perspective view, enlarged, of the manner of joining the corners of the box or 55 crate.

Referring to the drawings, and more particularly Figs. 1 and 4 thereof, it will be observed that my improved box or crate preferably comprises four substantially correspondingly shaped side-wall sections that are disposed with their longitudinal edges 60 abutting one another, as seen in Fig. 4, and are flexibly connected together by means of parallel flexible, metallic bands, 10—10, that are stapled or otherwise secured in a continuous manner along the transverse end 65 edges of said sections and parallel thereto. Each of the side-wall sections preferably 70 comprises a substantially rectangular-shaped plate, 11, of wood, veneer, or the like, that is elongated longitudinally and at or adjacent 75 its transverse end edges is provided with suitable cleats, 12—12. The cleats are disposed in upright position upon the side-wall section on the surface of said section that is adapted to form the interior of the 80 box when the latter is assembled. The faces of the cleats opposite the side-wall section are provided with longitudinally elongated 85 grooves, 13—13, and the corners or ends of said cleats are beveled or have portions cut 90 away at an angle of approximately forty-five degrees to the lower longitudinal edges, so that, when the box is folded or assembled, as shown in Fig. 1 of the drawings, these 95 beveled surfaces are adapted to abut each other and the cleats will be disposed at right angles to one another, with the grooves aligning and forming a continuous groove around the end of the box.

Suitable end-walls, 14, preferably of wood, 95 veneer, or the like, and of substantially the same thickness or gage as the side-wall sections, are inserted in the grooves, 13, of the cleats heretofore mentioned, in order to close the ends of the box when assembled.

The manner of assembly is comparatively simple and is performed in the following manner:—The end wall sections, 14, are placed upright in the cleats of the second side-wall from the left, as suggested in 105 dotted lines, Fig. 4, and the two adjoining side-wall sections are raised to a vertical position, so that the grooves in their respective cleats will engage the corresponding edges of said end-walls, 14. In order to 110 support the now vertically disposed side-walls, I prefer to make small openings,

15—15, in said vertical cleats adjacent their upper ends and so dispose said openings that they will open into the end portions of the grooves, 13, therein. When the vertical 5 side-walls have been placed in the position shown in Fig. 1, that is, in an upright or vertical plane, suitable brads or small nails, 16—16, are inserted into the recesses, 15, and the same are forced into or through the adjacent portion of the end walls, 14. This 10 will provide an open box so that the remaining side-wall section which is uppermost, may be closed down to form a cover or, if desired, may be thrown back to permit the 15 box to be packed. When the cover or uppermost side-wall section has been placed in proper position to close the box, the ends of the flexible metallic binding strip which extend beyond the adjacent corner of the box 20 are twisted together, as shown at 17, Fig. 3 of the drawings, to firmly and rigidly retain the box in assembled position. After assembly and the box has been closed, the nails, 16, may either be withdrawn or permitted to fall out of the openings as they 25 have then served their function, for it will be seen that the walls of the box are firmly held in position solely by the flexible metallic bands, 10.

30 For the purpose of providing a suitable guide that will insure the registration of the grooves, 13, in the cleats in order to provide a continuous channel when assembly is made, I prefer to continue the groove down one 35 beveled end face of each cleat to provide a recess, 18, while the opposite end face of each cleat is provided with a tongue, 19, upon its facing beveled portion. By means of this construction each tongue, 19, will fit into its 40 opposing recess, 18, and thereby guide the cleats when, in the process of assembly, they are moved so as to become disposed at substantially right angles to each other.

45 While I have herein shown certain specific means for carrying out my invention, I

do not wish it to be understood that I limit myself to the precise construction shown and described, for it will be obvious to others skilled in the art, that divers modifications may be made without materially departing 50 from the spirit of my invention. For example, the box may be made with end walls of polygonal shape, and the side walls may be comparatively narrow and of a number sufficient for the purpose of constructing a 55 box of desired section. Such modifications are understood as expressly included within the scope of my invention as expressed in the appended claim.

What I claim as new is:—

60 A knock-down crate including a plurality of sections flexibly connected together by suitable wires the ends whereof extend beyond the end sections, the flexible strip so formed being adapted to be folded transversely to form front, back, top and bottom panels, cleats beveled at their ends secured to the side portions of the strip upon one face thereof, each of said cleats having a tongue extending from one end and a recess 70 in its other end, said tongues being adapted to project into the recesses when the strip is folded, said cleats being formed with longitudinal grooves in their centrally facing faces, end panels adapted to be mounted 75 within said grooves, the upper portions of the two vertically disposed cleats being provided with transverse openings therein, pins adapted to be inserted in the openings in said cleats and to engage the end panels, 80 which pins constitute means for temporarily holding the front, back and bottom of the crate against the end panels.

85 Signed at Chicago, county of Cook and State of Illinois, this 22nd day of December 1915.

CHARLES Q. C. LEIGH.
